SEAT UNIT FOR A TRACTOR

Nolan Rhoades, Beloit, Wis., assignor to Simplicity Manufacturing Company, Port Washington, Wis., a corporation of Wisconsin

Original design application May 29, 1963, Ser. No. 75,115, now Design Patent 197,964, dated Apr. 14, 1964. Divided and this application Feb. 7, 1964, Ser. No. 78,935

Term of patent 14 years

(Cl. D14—3)

Fig. 2.

Fig. 1.

FIGURE 1 is a front perspective view of a seat unit for a tractor showing my new design; and

FIGURE 2 is a rear perspective view thereof.

The fragmentary portions of a tractor shown in broken lines are included for illustrative purposes only.

This application is a division of application Serial No. D. 75,115, filed May 29, 1963, and now Patent No. D. 197,964, granted April 14, 1964.

I claim:

The ornamental design for a seat unit for a tractor, as shown and described.
